(57) **CLAIM**

The ornamental design for a vehicle toolbox, as shown and described.

DESCRIPTION

FIG. 1 is a perspective view of a vehicle toolbox showing our new design;

FIG. 2 is a front view thereof;

FIG. 3 is a back view thereof;

FIG. 4 is an enlarged left view thereof;

FIG. 5 is an enlarged right view thereof;

FIG. 6 is a top view thereof;

FIG. 7 is a bottom view thereof; and,

FIG. 8 is a partially enlarged view of FIG. 3.

The broken lines shown on the drawings depict portions of the vehicle toolbox that form no part of the claimed design.
